DISK MARKER DISPENSER FOR GAME BOARDS

Michael J. Belmonte, East Haven, Conn.

Application February 15, 1957, Serial No. 44,884

Term of patent 14 years

(Cl. D52—2)

Fig. 1.

Fig. 2.

Fig. 3.

Fig. 1 is a perspective view of a disk marker dispenser for game boards showing my new design;

Fig. 2 is a view showing the dispenser in side elevation; and

Fig. 3 is a top plan view of the dispenser.

I claim:

The ornamental design for a disk marker dispenser for game boards, substantially as shown.
